No. 813,476.

PATENTED FEB. 27, 1906.

O. W. WITTMER,
BRAKE HANGER.
APPLICATION FILED NOV. 11, 1905.

UNITED STATES PATENT OFFICE.

OWEN W. WITTMER, OF COLUMBUS, OHIO.

BRAKE-HANGER.

No. 813,476.

Specification of Letters Patent.

Patented Feb. 27, 1906.

Application filed November 11, 1905. Serial No. 286,900.

To all whom it may concern:

Be it known that I, OWEN W. WITTMER, a citizen of the United States, residing at Columbus, in the county of Franklin and State of Ohio, have invented a new and useful 5 Brake-Hanger, of which the following is a specification.

This invention relates to brake-hangers for railway-cars, and has for its principal object to provide a brake-hanger of simple construction in which there are no rights and lefts, the hangers being interchangeable and adapted for use on either side of the car-truck.

A further object of the invention is to provide a brake-hanger which may be readily placed in position and locked in place without any screws, bolts, or other fastenings in addition to those now used in the manufacture and assembling of the truck.

20 A still further object of the invention is to provide a bolster-guide column and a brake-hanger having interfitting flanges and grooves, so that the hanger may be readily placed in position and may be supported directly from the column.

25 With these and other objects in view, as will more fully hereinafter appear, the invention consists in certain novel features of construction and arrangement of parts herein-30 after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a perspective view of a brake-hanger and bolster-guide column constructed and arranged 40 in accordance with the invention, the view showing also a brake-shoe and a portion of the brake-beam and illustrating also the upper and lower arch-bars of the structure in 45 section. Fig. 2 is a detail perspective view of the head of the bolster-guide column detached. Fig. 3 is a sectional view through the column and hanger.

Similar characters of reference are employed to indicate corresponding parts throughout the several figures of the drawings.

The upper arch-bar A and the lower arch-bar B of the structure may be of the ordinary construction, and between these is arranged 55 a bolster-guide column 10, that is provided

at its lower end with bolt-lugs for the passage of the usual bolts 11, by which the column is secured to the spring-plank. The upper end or head of the column is rectangular in form 60 and is provided with two vertical slots 12, arranged one in its inner face and the other in its outer face, the tops of the slots being open to permit the entrance of vertically-disposed parallel flanges 14, that are carried by the 65 outer end of the brake-hanger 15, and in assembling these parts it is merely necessary to slip the flanges 14 into the slots and then bolt down the arch-bar A in the usual manner, so that the hanger will be permanently secured 70 to the column without the necessity of employing any auxiliary fastenings.

The hanger 15 is in the form of an arm having strengthening-ribs 16 and 17 at its upper and lower edges, and from the front face of 75 the inner end of the arm extend pivot-ears 18, having openings for the passage of a pin or bolt 19, on which are hung the links C, the latter being connected to the brake-shoes D 80 in the usual manner.

It will be seen that the hanger is in the form of a simple casting which may be placed in any one of the columns, there being no rights and lefts, and of such construction that the column can be used on cars either with or 85 without brakes, merely adding the hangers where brakes are desired, so that the manufacturer is not compelled to keep on hand a large stock of castings or patterns.

Having thus described the invention, what 90 is claimed is—

1. In combination, a bolster-guide column having a recess, a brake-hanger including an arm arranged to fit within said recess and provided with pivot-ears for the support of 95 the brake-hanger links, said hanger being held from upward movement by the upper arch-bar.

2. In combination, a bolster-guide column having a recess, and a brake-hanger including an arm fitting within said recess and interlocking with the walls thereof to prevent 100 horizontal movement in any direction.

3. In combination, a bolster-guide column, the inner and outer faces of which are provided with vertical grooves, and a brake-hanger provided with a pair of spaced flanges 105 arranged to enter said grooves.

4. In a device of the class specified, a bolster-guide column, the opposite edges of which are provided with vertical grooves open at 110 the top, a brake-hanger having on its rear face

a pair of flange members arranged to enter said grooves and confined in place by one of the upper truss-bars of the truck.

5. In a device of the class specified, a brake-hanger comprising an arm having on one face a pair of projecting flanges and provided on its opposite face with a pair of spaced pivot-ears, a bolster-guide column provided with vertical grooves in its opposite edges, said grooves being open at the top to

permit the insertion of the flanges, and means for holding the brake-hanger in position.

In testimony that I claim the foregoing as my own I have hereto affixed my signature in the presence of two witnesses.

OWEN W. WITTMER.

Witnesses:

C. L. REAMER,
BARTON GRIFFITH.
